ANTI-BRIDGING DEVICE FOR FEED HOPPERS

Marvin L. Smallegan, Zeeland, Mich., assignor to Automatic Poultry Feeder Company, Zeeland, Mich., a corporation of Michigan

Application March 10, 1955, Serial No. 493,481

3 Claims. (Cl. 259—126)

This invention relates to means for preventing the formation of bridges in feed hoppers.

Many comminuted materials, when stored in bulk, such as in a hopper, tend to become compact and to form bridges. This is particularly true of poultry feed. This problem is particularly acute in machines in which the material is removed from the bottom of the hopper. These bridges form frequently and their formation prevents material from reaching the conveyor. The result is failure of the conveyor to remove material from the hopper.

While this problem has been recognized for many years and has been the subject of many different devices designed to prevent the formation of these bridges, no fully satisfactory anti-bridging device has heretofore been developed.

One of the greatest problems created by conventional anti-bridging devices is the fact that the more effective ones rotate the anti-bridging members in the feed. It requires substantial power to use devices of this design. The resulting high power requirements necessitate expensive, heavy-duty equipment. Furthermore, the operation of such machines produces a constant high energy demand, thus substantially increasing the operating cost of the equipment. This invention overcomes this problem by providing means which will positively eliminate bridging but which has a small power demand.

While this invention provides a positive means of eliminating the bridging effect, it also is of simple construction. This invention is so designed that it cannot hang up. That is, it cannot be rendered ineffective by becoming bound into the material. Many anti-bridging devices operate in one direction by means of gravity. Frequently the material becomes so compact that the weight of the anti-bridging device is insufficient to return it. This invention provides a bridging device which is positively operated at all times.

These and other objects and advantages of this invention will be readily seen by those acquainted with the design of poultry feeding equipment upon reading the following specification and the accompanying drawings.

In the drawings:

Fig. 1 is a side elevation view taken along the plane I—I of Fig. 2.

Fig. 2 is a sectional view taken along the plane II—II of Fig. 1 showing the diagrammatic outline of a typical hopper.

Fig. 3 is a fragmentary, sectional, elevation view taken along the plane III—III of Fig. 1.

Referring specifically to the drawings, the numeral 10 indicates a driven shaft. This shaft may be driven from any suitable power source by belts, chains or gears. It is preferably not connected directly to a prime mover because it is designed to operate at a slow angular velocity.

Mounted about the shaft 10 is a cradle 11. The cradle 11 consists of a pair of end spiders 12. The end spiders are identical, each consisting of an annular collar 14,

2

extending from which are four radial arms 15. The arms 15 are rigidly secured to the collar as by welding.

The arms 15, adjacent their ends, are apertured for reception of the threaded ends of the rods 16. As many rods 16 are employed as there are arms 15. The rods 16 are secured to the arms 15 by a nut 17 on each side. Thus, the spiders 12 are spaced apart substantially the full length of the rods 16. The rods 16 have a length equal to a major portion of the length of the driven shaft 10.

Seated within the annular collar 14 of each of the spiders 12 is an eccentric cam 18. The cams 18 are eccentrically mounted on the driven shaft 10 and are rigidly secured to the shaft so that rotation of the shaft will also rotate the cam. Rigidly secured to the inner face of each of the cams 18 is a disc-like plate 13 of greater diameter than the annular collar 14. These plates act as axial stops for the spiders 12. Thus, as the shaft is turned, the eccentric cams 18 slowly move the cradle 11 vertically and horizontally with relation to the shaft 10. It is this operation which prevents the bridging.

Mounted to the shaft 10 between the spiders 12 is a fin 20. The fin 20 is firmly affixed to the shaft so that it will rotate with it. Where there is a substantial distance on one end of the shaft between the wall of the hopper and the first of the spiders, an auxiliary fin 20a is provided.

Diametrically positioned from the fin 20 and between the spiders 12 are three somewhat S-shaped agitators 21. These agitators, like the fin, are designed to be rotated by the shaft. The use of the fin and the agitators prevents feed within the cradle 11 from forming a compact mass which will move with the cradle rather than being broken up by the cradle's motion.

As this invention is illustrated, four arms 15 are used upon the cradle. This particular arrangement is desirable because it balances the cradle within the feed, reducing its tendency to hang up or to rotate through the feed rather than to move vertically and horizontally within it. It is possible, however, in certain applications, to utilize this structure with a greater or a lesser number of arms 15. It will, of course, be recognized that when the number of arms 15 is changed, the number of rods 16 employed is also changed.

Fig. 2 shows this invention within the diagrammatic outline of a hopper 23. It will be seen that the rotation of the shaft 10 causes the cradle to reciprocate in all directions. This prevents the formation of bridges. If a bridge starts to form, it will be broken quickly before the conveyor at the bottom of the hopper becomes starved of feed. Since the cradle 11 is not rotated but is merely reciprocated within the feed, the power required to drive the mechanism is substantially less than that which would be necessary to form the rods 16 in a circular path through the feed. Even though the rotary motion is eliminated, the cradle will be completely effective in preventing the formation of troublesome bridges. Thus, substantially less horsepower is required to operate this invention than is normally required by equipment of this type.

While I have described a preferred embodiment of my invention, it will be recognized that various modifications of this invention may be made without departing from the principles thereof. Each of these modifications is to be considered as included in the hereinafter appended claims unless these claims by their language expressly state otherwise.

I claim:

1. In an anti-bridging mechanism having a driven shaft, the combination comprising: a pair of spaced cams eccentrically mounted to said shaft for rotation therewith; a pair of spiders, one seated about each of said

cams and adapted to be oscillated by said cams; said spiders each having radially projecting arms; rods extending parallel to said shaft between and securely affixed to said arms of each of said spiders adjacent the free ends of said arms.

2. In an anti-bridging mechanism having a driven shaft, the combination comprising: a pair of spaced cams eccentrically mounted to said shaft for rotation therewith; a pair of spiders, one seated about each of said cams and adapted to be oscillated by said cams; means extending between and connecting said spiders; radially projecting agitator elements secured to said shaft intermediate said spiders, the radius of said spiders being greater than the length of said agitator elements.

3. In an anti-bridging mechanism having a driven shaft, 15 the combination comprising: a pair of spaced cams eccen-

trically mounted to said shaft for rotation therewith; a pair of spiders, one seated about each of said cams and adapted to be oscillated by said cams; said spiders each having radially projecting arms; rods extending parallel to said shaft between and securely affixed to said arms of each of said spiders adjacent the free ends of said arms; radially projecting agitator elements secured to said shaft intermediate said spiders; the radial spacing of said rods from said shaft being greater than the length of said agitator elements.
